DESIGN FOR A TEXTILE FABRIC OR SIMILAR ARTICLE

Alexander J. Ostriker, New York, N. Y.

Application January 28, 1942, Serial No. 105,475

Term of patent 3½ years

To all whom it may concern:

Be it known that I, Alexander J. Ostriker, a citizen of the United States and a resident of the city of New York, in the county of New York and State of New York, have invented a new, original, and ornamental Design for a Textile Fabric or Similar Article, of which the following is a specification, reference being had to the accompanying drawing, forming a part thereof.

The figure is a plan view of a piece of the textile fabric or similar article showing my new design.

I claim:

The ornamental design for a textile fabric or similar article, substantially as shown.

ALEXANDER J. OSTRIKER.
